HANDRAIL

Louis Blum and William J. Horgan, Jr., Pittsburgh, Pa.,
assignors to Blumcraft of Pittsburgh, Pittsburgh, Pa., a
firm

Filed Dec. 19, 1967, Ser. No. 9,846

Term of patent 14 years

U.S. Cl. D13—7
Int. Cl. D25—01

FIG. 1 is a perspective view of a handrail embodying our new design;

FIG. 2 is a top view of a portion of a handrail embodying our new design;

FIG. 3 is a side view of the portion of the handrail illustrated in FIG. 2;

FIG. 4 is an end view of a handrail embodying our new design; and

FIG. 5 is an end view of a modified form of the handrail wherein the lower rail structure is broad and the posts are connected to the bottom side of said rail structure.

The posts shown in broken lines in the several views are disclosed for illustrative purposes only.

The handrail repeats as indicated and is shown fragmentarily to indicate indeterminate length.

We claim:

The ornamental design for a handrail, as shown and described.
